CLAIM

The ornamental design for a mesh basket, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front perspective view of a first embodiment of a mesh basket showing our new design; and, FIGS. 2-7 are perspectives which are respectively front, rear, left side, right side, top and bottom views thereof.

1 Claim, 7 Drawing Sheets
(7 of 7 Drawing Sheet(s) Filed in Color)# US D856,678 S
